UNITED STATES PATENT OFFICE.

HARRISON T. CLARK, OF SAN FRANCISCO, CALIFORNIA.

CONVEYER.

1,090,777.

Specification of Letters Patent. Patented Mar. 17, 1914.

Application filed May 25, 1912. Serial No. 699,657.

To all whom it may concern:

Be it known that I, HARRISON T. CLARK, a citizen of the United States, residing in the city and county of San Francisco, State 5 of California, have invented certain new and useful Improvements in Conveyers; and I do declare the following to be a clear, full, and exact description of the same, such as will enable others skilled in the art to which 10 it appertains to make and use the same, reference being had to the accompanying drawings, and to the characters of reference marked thereon, which form a part of this application.

15 This invention relates to improvements in conveyers and is particularly adapted for use as a distributing conveyer whereby by the use of the same any predetermined number of articles may be distributed to any desired point in quantities equal to said predetermined number, the object of the invention being to produce a means whereby the conveyer will count out a given number of articles by means of tilting distributing 20 paddles and then present a clear conveying surface ready for receiving a similar number of articles and again distributing them according to the predetermined number, the 25 entire operation being designed to be performed automatically and in a quick, ready and efficient manner.

30 A further object of the invention is to produce a simple and inexpensive device and yet one which will be exceedingly effective 35 for the purposes for which it is designed.

These objects, I accomplish by means of such structure and relative arrangement of the parts as will fully appear by a perusal of the following specification and claims.

40 On the drawings similar characters of reference indicate corresponding parts in the several views.

Figure 1 is a side elevation of the complete device showing the same with the 45 clear conveying surface ready for receiving the articles to be distributed. In this view the same is shown as with one of the side plates of a guiding chute for the conveyer removed in order that the entire structure of the device may be readily seen. Also the 50 view shows the structure partly broken out to show the overlapping paddles. Fig. 2 is a sectional view of the device showing the distributing paddles in tilted position. Fig. 55 3 is a detached view showing a releasing mechanism. Fig. 4 is a detached view

of a paddle showing a spring tension mechanism.

Referring now more particularly to the characters of reference on the drawings, I first provide a suitable guiding chute (not shown) having lower side boards 2 disposed on which in equal spaced relation are small journals 3. Disposed in each of said journals 3 is a small pin or shaft 4 and secured to each of said shafts 4 and projecting between the side boards 2 are paddles comprising an upper flat platform 5 having an offset shoulder 6 at its lower end from which projects another flat platform 7. In practice when the platforms 5 are set together the platforms 5 abut against the shoulders 6 and hence in the normal flat condition of the conveyer, the platforms 7 project underneath the platforms 5 and the platforms 5 present on their upper sides a continuous flat and unbroken surface as a conveyer or runway. Further since the end of one paddle abuts against the shoulder 6 immediately adjacent the journal point of the next paddle, this locks the second paddle against tilting as is apparent until the said first paddle is tilted which then releases the other paddle to be tilted and so on for each successive paddle, all for a purpose as will appear. In practice the pins 4 have downwardly projecting cranks 8 on one end connected with which are springs 9 fastened independently on the side boards 2 as at 10, the action of which springs holds the paddles 5-6-7 in their normal closed position presenting the uninterrupted flat surface as described. On the other ends of the members 4 are similar cranks 11 which normally lie about parallel with the members 5.

Projecting upwardly from each end of the conveyer is a post 12 turnably journaled in the upper end of which is a rod 13 carrying a small plate or bar 14 pivoted on which are a plurality of catches 15 limited in their 100 backward movement by pins 16.

In practice when the conveyer is in position the paddle member at the lower end of the entire conveyer has the platform 7 projecting clear without any other member over 105 it, and hence as the article to be distributed carries down the platform it will strike this projecting platform 7, tilt the entire paddle on its pivotal point 4 which will cause the projecting crank 11 to engage one of the 110 catches 15 and hold the paddle in tilted position, the article sliding off of the platform

and upon an apron or other conveying means which will carry it to any point desired. This operation releases the next paddle from its locked position as heretofore set forth and leaves the platform 7 clear, hence the next article moving downwardly will strike the platform 7 of that paddle and tilt such paddle and this operation will be repeated for as many times as there are articles to be distributed.

The first one of the paddles which would be the uppermost one is not provided with a platform 5 but the platform 7 is journaled directly to its bearing and then a runway leads to the same, the overlapping platform 5 abutting normally flush with said runway. 1 is not provided with a crank 11 but is provided with a straight projecting rod 11^a which when this last member 7 is tilted moves upwardly and engages an obliquely sloping member 17 projecting from the side of the member 14 into the path of said pin 11^a. This operation then swings the member 14 outward, releases all the catches 15 from the pins 11 and then the springs 9 pull all the paddles back into normal closed position ready for distributing another number of articles.

Each of the members 5 at its outer end is provided with a pin 5 adapted to impinge on the top edge of the side board 2 to prevent such member 5 from having a tendency to tilt the wrong way and render an uneven surface between it and its adjacent member 5.

In order to prevent the bar 14 from swinging on its pivotal point which would release the members 11 from the catches 15 prematurely I provide projecting shoulders 18 on the posts 12 against which inner edge of the member 14 projects and is held in frictional contact therewith by means of springs 19 secured to the posts 12 and projecting over the side of said member 14.

While my improved distributing conveyer is adapted for use whenever found desirable, still I have particularly designed it for use in bakeries for distributing balls of dough from the rounder to the proofing conveyer where it is necessary to distribute in series of 4, 6 or more where found desirable. At the present time these balls of dough which come from the rounder are lifting into the proofing conveyer by hand, but by the use of my improved distributing conveyer they may leave the rounder and pass directly upon my conveyer which will distribute them in any desired number upon any desired apron or other conveyer which will lead them to the proofing conveyer as will readily be seen.

While I have shown a particular form of catch for the paddles and a particular form of resilient means for returning them to exact position, still in practice many and

various forms will be found just as adaptable and hence I have merely shown one complete form of the entire combination in this application, since the main feature of the device is the tilting paddles and the other details are merely incidental elements thereto in order to make an operative device.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention.

Having thus described my invention what I claim as new and useful and desire to secure by Letters Patent is:

1. A device of the character described comprising a plurality of paddles journaled at points intermediate their ends, each paddle interlocking with its adjacent paddle in such a manner as to prevent any one of said paddles from tilting until the preceding paddle has tilted, each of said paddles being free to tilt on its journaled point independently of its preceding paddle as soon as its preceding paddle is tilted, as described.

2. A device of the character described comprising a plurality of paddles journaled at points intermediate their ends, each paddle interlocking with its adjacent paddle immediately adjacent its journaled point whereby each paddle acts as a lock against the independent tilting of its adjacent paddle until it is tilted, as described.

3. A device of the character described comprising a plurality of paddles journaled at points intermediate their ends, each of said paddles interlocking with its adjacent paddle at a point immediately adjacent its journaled point whereby one of said paddles cannot tilt until its preceding paddle has first tilted, all of said paddles when in locked position forming a smooth uninterrupted surface, as described.

4. A device of the character described comprising a plurality of paddles journaled at points intermediate their ends, each paddle being provided with a shoulder immediately adjacent its journal point, those portions of the paddles on opposite sides of said shoulder being in different horizontal planes, each paddle overlapping its adjacent paddle and abutting against said shoulder whereby each paddle acts as a lock against independent tilting of its adjacent paddle until it is tilted, as described.

5. A device of the character described comprising the combination of a flat runway, of a plurality of paddles pivotally

mounted in successive order, a bar pivotally mounted at a spaced distance from said paddles, a plurality of depending stop members on said bar, means on each paddle for engaging one of said stop members and means on one of said paddles for engaging said bar to move it on its pivotal point to release said stop members from the engaging means on said paddles, as described.

10 6. A device of the character described comprising a plurality of paddles disposed in successive order forming a smooth uninterrupted surface, each of said paddles

being journaled intermediate its ends, a projecting pin on the side of each paddle, such pin being disposed at substantially right angles to said paddle, a catch adapted to engage each pin, and means for releasing said pin from said catch, as described.

In testimony whereof I affix my signature 20 in presence of two witnesses.
